United States Patent Office.

GEORGE D. WILLIAMS, OF CHICOPEE, MASSACHUSETTS.

Letters Patent No. 72,709, dated December 24, 1867.

IMPROVED BREAD-CUTTER.

The Schedule referred to in these Letters Patent and making part of the same.

TO ALL WHOM IT MAY CONCERN:

Be it known that I, GEORGE D. WILLIAMS, of Chicopee, Hampden county, Commonwealth of Massachusetts, have invented a new and useful Improved Bread and Meat-Slicer; and I do hereby declare that the following is a full and exact description thereof, reference being had to the accompanying drawings, and to the letters of reference marked thereon. In the drawings—

Figure 1 is an end view, and

Figure 2 a plan view of my device.

This invention is for the purpose of cutting up bread into slices of any desired thickness, in a neat and convenient manner. It may also be used to chip beef, dried venison, &c.

In construction it is formed of a feed-shelf, A, having at one end the cutting-device, consisting of a knife, B, working in a guide-frame, C. This knife B is connected at one end to the lower corner of the frame C, and is arranged so that when brought down to its furthest, its edge has passed the plane of the feed-shelf A. The guide-frame C is formed of two parallel arches *a* and *b*, placed beside each other, and leaving room for the knife-blade to work in between them, and keeping the latter always in a position at right angles in its plane to the bottom of the trough forming the feed-shelf. The end of the knife-blade is slotted at D, through which slot a pin, E, is passed, it being fitted into a hole cut through the projecting portions of the frame C at *f*, and forming a pivot for the knife-blade. The slot D in the latter allows a sawing motion to be given to it, which is especially useful in cutting warm or very fresh bread. The knife-blade is only bevelled on one side of the edge, the outside from the shelf, which draws the body of the loaf towards the knife, and prevents the slice being cut from decreasing in thickness, by keeping its outside lower edge close up against the gauge-bar F. This gauge-bar stretches across from side to side, in front of the lower part of the frame C, and its top edge is higher than the plane of the feed-shelf. It is made adjustable from the line of the knife by being set on pins *g* and *g'*, which pass through holes in the ends of the bar. A set-screw, G, clamps it in any position it may be set. There is a hole, *h*, in the end of the knife-blade, into which the pin E may be inserted after being taken from its position through the slot D and in the frame. This allows the knife to be handled as ordinarily, except that it still is confined to a vertical plan, and is convenient in cutting meat, &c. Soft-metal rests are placed in the frame at *k* *k*, where the edge of the knife rests, to prevent it from getting dulled by contact with the metal forming the frame.

The operation of this device is as follows: The loaf is placed on the feed-shelf, and, guided by the side of the same, is pressed up against the gauge-bar, which is set for the width of slice required; it is then cut up by the knife, it being pressed up against the gauge as each slice is cut, and tumbles off.

In this manner I obtain a simple, handsome, and effective device for the purpose, which is cheap enough to be used in every family.

And having described my invention, I wish to claim as follows:

The device consisting of the shelf A, guide-frame C, knife B, and adjustable bar F, combined and arranged substantially as and for the purpose shown.

GEO. D. WILLIAMS.
